SEGMENTAL GEAR

Herman T. Overbey, Wadesboro, N. C., assignor of
one-half to J. F. Martin, Wadesboro, N. C.

Application February 5, 1940, Serial No. 317,432

5 Claims. (Cl. 74—448)

The present invention relates to gear construction and has for its primary object to provide a segmental gear by means of which sections of the gear may be conveniently removed and replaced should the teeth thereof become broken or mutilated, and without necessitating a complete dismantling of the gear or shaft on which the gear is mounted.

An important object of the present invention is to provide a segmental gear construction in which each of the segments are of duplicate formation for interchangeable assembly and providing an attaching plate for the sides of the gear segments and provided with lugs seated in recesses in the segments to secure the segments against movement relative to the plate.

A still further object is to provide a segmental gear construction of this character in which each of the segments have their inner edges conformably fitted on the shaft or bearing on which the gear is mounted to assist in supporting each of the gear segments in a rigid assembled position.

A still further object is to provide a device of this character of simple and practical construction, which is strong and durable, relatively inexpensive to manufacture and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which—

Figure 1 is a side elevational view of one embodiment of the invention.

Figure 2 is an edge elevational view thereof.

Figure 3 is a transverse sectional view taken substantially on a line 3—3 of Figure 1.

Figure 4 is a plan view of one of the gear segments.

Figure 5 is a fragmentary sectional view taken substantially on a line 5—5 of Figure 1, and showing an anchoring screw for the gear segment to secure the same against displacement upon removal of one of the assembly plates.

Figure 6 is a side elevational view of a modified attaching plate and collar construction.

Figure 7 is an edge elevational view thereof.

Figure 8 is a transverse sectional view taken substantially on a line 8—8 of Figure 6.

Figure 9 is a side elevational view of a further modification.

Figure 10 is an edge elevational view thereof, and

Figure 11 is a transverse sectional view taken substantially on a line 11—11 of Figure 9.

Referring now to the drawings in detail, and with particular reference to Figures 1 to 5 inclusive, the numeral 5 represents the plurality of gear segments, which preferably comprise four in number to complete the gear and including the toothed outer edge 6 and the arcuate inner edge 7, adapted to rest against the hub or collar 8 formed on an assembly plate 9. Each of the segments is provided with an oval-shaped recess 10 in each face thereof and adapted to conformably receive the lug 11 formed on the inner face of the plate 9.

The plate 9 is positioned at one side of the segment 5 and at a relatively opposite side is positioned an assembly plate 12 likewise having lugs 13 formed on the inner face thereof for conformably seating in the recesses 14 of the adjacent face of the gear segments. The plate 12 is provided with a central opening 15 for receiving the collar 8 and the plates are secured in assembled position against opposite sides of the gear segments by means of bolts 16 extending therethrough. The collar 8 is provided with the usual bore 17 for accommodating a shaft and extending longitudinally of the bore is the keyway 18 for anchoring the shaft in the bore of the collar. A set screw 19 may also be employed for securing the collar against movement on the shaft.

When replacing any of the segments the plate 12 preferably is removed and in order to prevent displacement of all of the segments screws 20 are inserted through the segments for attaching the same to the plate 9.

In the form of the invention illustrated in Figures 6 to 8 inclusive the gear segments are indicated at 21 and the assembly plates 22 and 23 are of identical construction and each provided with a hub or collar 20 for projecting outwardly from the outer faces of each of the plates.

In this form of the invention the inner edge of the segments bear directly on the shaft 25 and the assembly plates are secured in position at opposite sides of the gear segments by bolts 26.

In the form of the invention illustrated in Figures 9 to 11 inclusive, a single assembly plate 27 is provided at one side of the gear segments 28 and secured thereto by bolts 29. The outer face 50 of the plate is provided with the collar 30 and the shaft 31 has a reduced portion 32 against which the inner edge of the gear segments abut and the shaft is further reduced as shown at 33 for snugly fitting in the bore of the collar 30. 55

A shoulder 34 is formed between the reduced portion 32 of the shaft and the main portion of the shaft which abuts the face of the gear segment opposite from the plate 27 and a similar shoulder 35 is formed between the reduced portions 32 and 33 of the shaft which abuts against the plate 27.

It will be understood that in each form of the invention the plates are formed with the lugs 10 which conformably seat within the recesses formed on the face of the gear segments, and in each instance the attaching bolts are countersunk in the plates, and also in the gear segments in the form of the invention illustrated in Figures 15 9 to 11 inclusive.

It is believed the details of construction, advantages and manner of use of the device will be readily understood from the foregoing without further detailed explanation.

Having thus described the invention, what I claim is:

1. A segmental gear construction comprising a plurality of duplicate gear segments, each segment including a toothed outer edge and an 25 arcuate inner edge, a member disposed axially of the segments against which the inner edge of each segment abuts, a plate positioned flatwise against the segments, interengaging means between the opposed face of the plate and the opposed face of the segments and means for removably securing the segments individually to the plate.

2. A segmental gear construction comprising a plurality of duplicate gear segments, each segment including a toothed outer edge and an arcuate inner edge, a member disposed axially of the 30 segments against which the inner edge of each segment abuts, a plate positioned flatwise against

the segments, interfitting lugs and recesses carried by the opposed faces of the plate and the opposed faces of the segments to secure the segments in a fixed position when flatwise engaging the plate and means for securing the segments individually flatwise against the plate. 5

3. A segmental gear construction comprising a plurality of duplicate gear segments, each segment including a toothed outer edge and an arcuate inner edge, an assembly plate having a 10 hub and interfitting lugs and recesses carried by the opposed face of the plate and the opposed faces of the segments for securing the segments to one face of the plate with the inner edges of the segments bearing on the hub. 15

4. A segmental gear construction comprising a plurality of duplicate gear segments, each segment including a toothed outer edge and an arcuate inner edge, a pair of assembly plates, a hub on one of the plates against which the inner 20 edges of the segments abut and interfitting lugs and recesses carried by the opposed face of the plate and the opposed faces of the segments for securing the plates to opposite sides of the segments. 25

5. A segmental gear construction comprising a plurality of duplicate gear segments, each segment including a toothed outer edge and an arcuate inner edge, a pair of assembly plates positioned flatwise at opposite sides of the segments, means for securing the segments to one 30 of the plates, the other of said plates retaining said securing means against displacement, common fastening means connecting both plates to the segments and interfitting lugs and recessed between the inner faces of the plates and the adjacent sides of the segments. 35
